UNITED STATES PATENT OFFICE.

JONATHAN R. MATTER, OF HARRISBURG, PENNSYLVANIA.

RAILWAY-SWITCH.

SPECIFICATION forming part of Letters Patent No. 535,992, dated March 19, 1895.

Application filed December 17, 1894. Serial No. 532,046. (No model.)

To all whom it may concern:

Be it known that I, JONATHAN R. MATTER, a citizen of the United States, residing at Harrisburg, in the county of Dauphin and State of Pennsylvania, have invented certain new and useful Improvements in Railway-Switches, of which the following is a specification.

This invention relates to that class of railway switches which are operated by the weight of the motor or car while the wheels are passing over certain lever-connected projections rising above the surface of the rail.

The object of my invention is the throwing of the switch by separate cars or successive trains avoiding the necessity of employing a switch-tender or compelling some one to descend from the car at each junction. The combination of mechanical elements used to attain this end consists of a prong-ended hooking rod, delivering motion to a vibrative compound track-plate, switch-rod and tongue, the whole set in motion, held inoperative during a certain period governed by the speed of a passing train, and reset for a following train, by a system of lever connected knobs projecting above the surface of the rail as more particularly described hereinafter.

In the accompanying drawings like numerals and letters indicate the same parts in the several figures.

Figure 1, shows a general plan view of the parts and connections. Fig. 2, shows the straight spring-piece beneath and operating the prong-rod. Fig. 3, shows the tongue of the switch with the flat spring attached to its under surface. Fig. 4, shows the track-knob near the switch with its attached lever and the latching stop upon the prong-rod; Fig. 5, the guard knob remote from the switch with the lever attached. Fig. 6, shows the track-knob and the pivoted block remote from the switch. Fig. 7, shows the bar and brace serving motion to the prong-rod, and the spiral spring and accessories used to return the prong-rod to its first position; and Fig. 8, shows the single knob for throwing the switch when operated by a depression wheel borne by the car, as specified.

In this description the point marked, X, Fig. 1, is regarded as beyond the switch and that lettered, Y, as situated before and upon the track leading to the switch.

The tongue of the switch, pivoted to the rails at their meeting point upon one side of the track in the usual way, is numbered, 1. 55 A flat spring, 2, is fastened by one of its ends toward the point of the said tongue, the other end of this spring being attached, at the point numbered 3, to the outer end of the switch-rod, 4. The inner end of the switch-rod is 60 pivotally joined to a plate, 5, possessing angular notches in its boundary at opposite points near the top and bolted to or cast integral with a second and somewhat larger plate, 6, beneath it. The said lower plate, 6, 65 is of the same general outline as plate, 5, the entering angles of the former being nearer together and advantageously more obtuse than those of the latter plate. The smaller plate is fixed upon the larger so that the distance between their edges is approximately 70 the same throughout and both vibrate together about a pivot through their common center. The said pivot may project directly from one of the cross-ties, but the preferred construction 75 makes use of a bed-plate, 7, bolted to the ties and upon which the movable plates rest as shown in Fig. 1. The entering angles at opposite points in the edge of the plate, 6, are occupied alternately by a corresponding bend in 80 a flat spring, 8, which serves the purpose of preventing the movement of the plates unless acted upon by a sufficient force to throw the switch. This spring is fast at its outer end to the bed-plate. From the lower edge of 85 plate, 6, the straight side as shown in the drawings, there projects a round tooth or pin, 9, perpendicular to the said plate. This upright pin engages a semicircular indentation in one end of a spring-piece, 10, a considerable portion of which toward the end provided 90 with the said indentation is formed wide and flat and rests broadside upon and is pivoted to the bed-plate, 7. The remainder of the said spring-piece is formed into a flexible 95 section terminating in a block, 11, which possesses a groove upon its upper surface, or the said block may be bored for the passage of the long, prong-ended rod, 12. Near the prong and upon the upper surface of the rod, 12, is 100 a raised portion or lug, 13, and resting upon the said lug is one end of a lever, 14. This lever is shown best in Fig. 4. It is provided with a fulcrum at a suitable point and its

outer end extends through the web of the rail joining pivotally an upright piece outside the rail. The said piece passing upward through the tread of the rail is capped by a 5 rounded end or knob, 15, which, in its normal position, rests above the wheel-bearing surface of the rail. The said knob and its attachments as well as the lug upon the prong-rod are located near the switch.

10 A joint, 16, and a sleeve-block, 17, bolted to the track, permit the prong-rod to adapt itself to ordinary curvature.

Bolted to the ties at the lower end of the prong-rod is the casting, 18, so constructed as 15 to afford a suitable support for the sliding end of the rod, and a fixed base for one end of a spiral spring, 19, the opposite end of said spring touching the end of the prong-rod. A modification of the said casting, 18, affords, in 20 addition to the features named and directly above the end of the rod, side bearings for the trunnions of an oscillating piece of the form set out below and shown in Fig. 8.

A straight bar, 20, is fast at one extremity 25 to the end of the prong-rod, 12, at approximately a right angle and parallel with the plane of the track. The brace, 21, unites prong-rod and bar to strengthen the connection between them. Immediately before its 30 passage through the rail as shown in Fig. 7, the bar, 20, is supported upon and near the end of a lever, 22, with fulcrum upon the rail at the point, 23; the other arm of the said lever being attached, pivotally, to an upright piece 35 passing through and ending, somewhat above the groove of the rail, in the guard-knob, 24, similar in shape to the knob mentioned previously. Passing through a suitable aperture the bar, 20, ends near and slightly below 40 one corner of a triangular block, 26, the said block being pivoted near a second corner to the outside surface of the web of the rail and over-balanced by a weighted projection, 27. The third corner of the said block is extended 45 upward through the over-hanging part of the rail and ends in a knob, 28, similar to the others. The weight of bar, 20, upon lever, 22, maintains knob, 24, at a suitable distance 50 above the level of the wheel-bearing surface of the rail, and the weighted projection, 27, exerts the same influence upon knob, 28. The guard-knob, 24, and knob, 28, are not situated exactly beside each other directly across the rail, but, knob, 28, leads the other a short 55 distance toward the switch. Omitting these track-knobs and their lever connections, one form of my invention requires for its operation a block, 29, best shown in Fig. 8, resting in the side bearings raised from the casting, 60 18; the lower end of this block being pivotally yoked to the end of the prong-rod. This pattern of my switch is thrown by the contact of a wheel or shoe borne by the car and adapted to be depressed by a person upon the car; 65 the operating wheel being returned to its first position by a spring as shown in Fig. 8.

The operation of my device may be ex-

plained by first taking notice of cars approaching from the point, X, in Fig. 1, above the switch. The wheels of cars from that direction do not throw the switch. Whatever may be the position of the tongue, 1, it is simply pressed to one side by the passing wheel and immediately returned to its place by the spring attached beneath it, as shown in Fig. 3. 75 The knob, 15, is depressed during the passage of the wheel and raised immediately thereafter by the weight of the inner arm of lever 14. The next knob struck is, 28, and the block is merely tilted regaining its place by the fall 80 of the weight at 27. While knob, 28, is down the guard-knob, 24, is reached and by its connected levers raises bar, 20. Under these conditions the block, 26, has been so turned that the elevated extremity of bar, 20, passes behind the said block and all the parts involved are reset upon the departure of the wheel as the explanation of their structure indicates.

Let the car approach from the point, Y, below the switch. The tongue of the switch occupies one of two positions, owing to the nature of my invention, directing the cars upon the branch track or allowing them to pass straight onward as shown in Fig. 1. The salient angle of plate, 6, affords no stable resting place 95 for the latching angle of the spring, 8. Looking toward X it will be seen that the hook upon the right arm of the prong engages the notch on that side of plate, 5. A wheel from Y, would, therefore, produce a series of mechanical movements beginning with the depression of the guard-knob, 24, Fig. 5, thereby raising the end of bar, 20, Fig. 7, into a position from which it may be pushed directly backward in the direction of Y by the 100 lowest corner of the block, 26, Fig. 6, set in motion as the wheel reaches the knob, 28. It will be seen that both the guard-knob and that upon the block must be acted upon in the manner described in order to throw the 105 switch. A carriage or wagon driven across the track would do no harm, one knob only being likely to be affected. The rearward journey of the bar, 20, bears with it the prong-rod, 12, and compresses the spring, 19, shown 110 in Fig. 7. At the limit of the backward travel of the prong-rod, the lug, 13, Fig. 4, no longer supports the end of the lever, 14, which drops in front of the said lug and prevents the reaction of the rod. The engaged 115 hook upon the end of the right arm of the prong has drawn plates, 5 and 6, far enough to carry the angle of the spring, 8, over the apex of the salient angle of plate, 6, and the tongue of the switch is drawn toward the 120 main track. The pressure of the spring, 8, upon the slanting edge of the said plate aids the complete movement of the switch. The first wheel that reaches and depresses the track-knob, 15, Fig. 4, near the switch liberates the prong-rod which moves forward without altering the position of the switch. At 125 the same time the spring-piece, 10, Fig. 2, moves the prong laterally bringing the left

hand hook into the adjacent angle of plate, 5. The switch will now direct the passing train upon the siding or branch track and is not again disturbed until the guard and track-knobs are further operated upon, when the switch will be returned to the situation in Fig. 1. It will be seen that the distance from the knob, 15, to the knob, 28, must be more than sufficient to contain the passing train, otherwise the switch would be oppositely thrown with resulting confusion. Joints, 16, in the prong-rod permit it to yield readily to the influence of the said spring-piece as above described and to follow a curving track.

Having thus described my invention in detail, what I claim, and desire to protect by Letters Patent, is—

1. In a railway switch operated by passing car wheels, the combination of the switch-tongue having the flat spring attached beneath it toward the point, the said spring extending backward and connecting with the switch-rod, the two joined plates having a common pivot and motion and each possessing an edge indented at two points separated by a projecting area, the indentations of the lower and larger plate adapted to be alternately occupied by a corresponding bend in a flat spring which is fixed by its outer extremity to the ties or bed-plate, the indentations of the smaller and upper plate adapted to be occupied alternately by inwardly projecting hooks terminating the arms of a prong at one end of the rod, the said lower plate and the said prong-rod being, respectively, in pivotal and sliding contact with a pivoted spring-piece, the said upper plate being pivotally attached to the said switch-rod, the raised portion or lug upon the rod near the prong, 40 the lever possessing a suitable fulcrum and having one end resting upon the said lug and its other end connected to the upright piece which projects slightly above the wheel-bearing surface of the rail, the said prong-rod being upheld at intervals by grooved or bored supports upon or within which it may slide and suitably jointed to follow a curving track, and mechanism by which the said prong-rod may be drawn in one direction when cars approach the switch and subsequently returned to its forward position in the manner substantially as shown and described for the purpose specified.

2. In a railway switch operated by passing car wheels, the prong-ended rod provided with inwardly projecting hooks terminating the arms of the prong, the said rod having, upon its upper surface near the prong, a raised portion or lug, in combination with a lever normally resting upon the said lug and extending at right angles with the said prong-rod, the said lever having a fulcrum at a suitable point and pivotally joined at its outer end to an upright piece which passes through the wheel-bearing surface of the rail and ends in a knob raised somewhat above the said surface, the whole so constructed and arranged

that the said lever may drop before the said lug, when the said prong-rod is drawn backward, and be raised from that position by the depression of the said knob, and mechanism for operating the said prong-rod substantially as shown and described for the purpose set forth.

3. In a railway switch operated by passing car wheels, the prong-ended rod provided with inwardly projecting hooks terminating the arms of the prong, in combination with the bar rigidly attached to the straight end of the said prong-rod and perpendicular thereto in the plane of the track, the said bar supported inside the rail by and near one end of a lever which is provided with a suitable fulcrum and pivotally joined at its farther extremity to an upright piece, the said upright piece passing through the wheel-bearing surface of the rail and ending in a knob at rest somewhat above the said surface, the said bar passing through the rail and ending near the lower corner of a pivoted block, the said block, overbalanced by a weighted projection, and having one part extending upward and adapted to pass through the over-hanging portion of the rail and ending in a knob normally raised somewhat above the said surface of the rail and slightly in advance of the first knob along the rail, the whole so constructed and arranged that the switch can only be thrown by the depression of both knobs substantially in the manner shown and described.

4. In a switch operated by passing car wheels, a spring-piece having one portion broad, flat and comparatively rigid, the said rigid portion provided at the end with a semi-circular indentation and having a pivot hole, the remainder of the said spring-piece being intentionally flexible and terminating in a grooved or bored block substantially as shown and described for the purpose set forth.

5. In a railway switch operated by passing car wheels, the combination of a switch tongue and rod with the two joined plates having a common pivot and motion, each of the said plates possessing an edge indented at two points separated by a projecting area, the indentations of the lower and larger plate being alternately occupied by a corresponding bend in a flat spring which is fixed by its outer extremity to the track or bed-plate, the indentations of the upper and smaller plate adapted to be alternately occupied by inwardly projecting hooks terminating the arms of a prong at one end of a rod, the said lower plate and the said prong-rod being, respectively, in pivotal and sliding contact with a pivoted spring-piece, the raised portion or lug upon the upper surface of the said rod near the prong, the lever having its inner end resting upon the said lug and its outer end connected to the upright piece ending in the knob, the spiral spring so placed as to return the prong-rod forward, the bar attached rigidly to the said rod perpendicular thereto in the plane of the track, the lever supporting the said bar inside

the track and having its farther end joined to an upright piece extending through the wheel-bearing surface of the rail and ending in the knob raised above the said surface, the pivoted and over-balanced block having the knob normally raised above the said surface and slightly in advance of the first knob along the rail, the lower corner of the said block being so situated as to strike the said bar passing through the rail and to move the same when the said track-knobs are depressed in the manner shown and described for the purpose set forth.

6. In a railway switch operated by passing car wheels, the combination of the tongue having the spring attached beneath it toward the point, the said spring extending backward and connecting with the switch-rod, the two joined plates having a common pivot and motion and each possessing an edge indented at two points separated by a projecting area, the indentations of the lower and larger plate adapted to be alternately occupied by a corresponding bend in the flat spring which is fixed by its outer extremity to the track or bed-plate, the indentations of the upper and smaller plate adapted to be alternately occupied by inwardly projecting hooks terminating the arms of the prong at one end of the rod, the said lower plate and the said prong-

rod being, respectively, in pivotal and sliding contact with a pivoted spring-piece, the raised portion or lug upon the upper surface of the said rod near the prong, the lever having its inner end resting upon the said lug and its outer end connected to the upright piece ending in the knob, the spiral spring so placed as to return the prong-rod forward, the bar attached rigidly to the said rod perpendicular thereto in the plane of the track, the lever supporting the said bar inside the rail and having its farther end joined to an upright piece extending through the wheel-bearing surface of the rail and ending in the knob raised above the said surface, the pivoted and over-balanced block having the knob normally raised above the said surface and slightly in advance of the first knob along the rail, the lower corner of the said block being so situated as to strike the said bar passing through the rail and to move the same when the said track-knobs are depressed in the manner shown and described.

In witness whereof I hereunto set my hand in the presence of two witnesses.
